L. R. TALBERT

RIB LOCK FOR UMBRELLAS

Filed July 9, 1925

Patented Sept. 28, 1926.

UNITED STATES PATENT OFFICE.

LEE R. TALBERT, OF LONG BEACH, CALIFORNIA.

RIB LOCK FOR UMBRELLAS.

Application filed July 9, 1925. Serial No. 42,465.

My invention is a rib lock for umbrellas adapted to retain the ribs in snug relation against the umbrella rod when the umbrella is folded and to allow rolling of the lock on to the handle to allow opening of the umbrella.

My invention in particular comprises a type of resilient ring or elastic bracelet which may be inserted over the end or 10 around the handle of the umbrella and fastened in place with a suitable catch, bayonet or screw threaded joint. The rib lock is made of a tight helically coiled spring which may be passed around the handle or the ribs 15 of the umbrella at the upper ends thereof and by means of a clasp of a suitable type hold the wire grip lock in position.

My invention will be more readily understood from the following description and 20 drawings, in which;—

Figure 1 is a perspective view of an umbrella showing my rib lock in position engaging the upper ends of the ribs and holding them in snug position against the rod.

Fig. 2 is a perspective view of the upper 25 end of the handle showing the rib lock rolled off the ribs and on to the handle.

Fig. 3 is a developed view of the rib lock, 30 opened up in substantially a straight line, showing the type of coil spring used and the bayonet type fittings for each end.

Fig. 4 is a perspective view of the plug 35 end of a bayonet fitting.

Fig. 5 is a view of the socket end of the 40 bayonet fitting.

Fig. 6 is a view of the rib lock bent into a circle with the bayonet end clasped holding the device in a circle.

Fig. 7 is another type of joint showing 45 a screw threaded connection between the two ends and the spring.

Fig. 8 is a sectional view of still another type of joint showing prongs to engage in a flanged socket.

Fig. 9 is another type of rib lock in which 50 the helical spring is soldered or welded at the ends forming a continuous helix bent into a circle.

In the drawings, the umbrella is designated generally by the numeral 1, having 55 a handle 2, a rod 3, ribs 4 and a cover 5. The rib lock is designated generally by the numeral 6 and is shown in Fig. 1 tightened around the upper ends of the ribs and in

Fig. 2 as being rolled upwardly on the 55 lower end of the handle.

Referring to Figs. 3 to 6, the lock is formed by a tightly coiled wire 7 coiled into the form of a helix. At one end is a bayonet plug 8 having a barrel section 9, a reduced stem 10 and a prong 11 projecting from one side of the stem adjacent its outer end. The plug is secured to the open end of the spring by inserting the barrel section 9 within the spring and preferably soldering or welding the spring and barrel together. The socket end 12 of the bayonet joint 13 is formed of a ring 14 of sufficient external diameter to fit snugly in the end of the spring opposite the 70 plug 8 and to be secured therein preferably by soldering or welding. The ring has an internal circular section 15 of substantially the same diameter as the stem 10 of the plug and has a slot 16 therethrough for the 75 insertion of the prong 11. After inserting the prong through the slot it is given a turn and seats in a recess 17 formed in the under face of the ring 14.

The plug and socket are preferably secured to the ends of the spring so that the 80 spring will require to be slightly twisted as if winding tighter to insert the prong through the slot and in tending to unwind the spring draws the prong into the recess 85 17. The tension of the spring then draws the prong into tight engagement with the recess and prevents them becoming accidentally unlatched. When so connected the rib lock has the appearance shown in Fig. 6. 90

In the construction of Fig. 7 an internally 95 screw threaded socket 20 having a cylindrical outside surface 21 is secured in one end of the spring 7 in a manner above described. This socket may have a base 22 if desired or may be made in the form of a short tube or nipple. The plug 23 has a cylindrical end 24 to fit in the end of the coiled wire spring at its opposite end from the socket and has a screw threaded stem 25.

In the operation of securing the fastening of Fig. 7 the spring 7 is preferably twisted tighter several or more turns than its usual normal position and the screw threaded stem 105 25 is inserted in the screw threaded socket 20 so that the tendency of the spring to unwind screws the two ends together and holds them thus tightly locked.

In the construction of Fig. 8, a socket 30 shown as a short tube with an inwardly extending flange 31 is secured inside the spring 7, and the plug 32 having a cylindrical base 33 is secured in the other end of the spring. A pair of spring prongs 34 having hook-shaped ends 35 are inserted in the socket so that the hooks engage the inner surface of the flange 31 and thus holds the two ends 10 of the spring in tight engagement.

In Fig. 9 the two ends of the spring 7 are indicated by the numeral 36 as being secured together by soldering, welding or the like, thus forming an elastic ring of the size desired.

It is intended that the elastic wire ring when placed on the handle of an umbrella will be left thereon, hence the different types of clasps may be made to have a tight fit.

20 My invention may be made up of any suitable materials, being made of expensive material to harmonize with costly umbrellas or to be made of relatively cheap spring steel wire if desired. My invention may also be

modified to suit particular adaptations of the 25 ring elastic spring without departing from the spirit of my invention.

Having described my invention, what I claim is:—

In a resilient ring having a wire twisted 30 to form a helix, such wire being formed of spring metal, a socket member formed of an annular ring having a slot on the inner periphery of the ring and a recess on the inner surface, the said ring being attached to 35 one end of the wire coil, a plug attached to the other end of the wire coil, such plug having a barrel section of substantially the interior diameter of the coil and a reduced stem extending outwardly therefrom, the 40 stem having a prong adapted to pass through the slot in the ring and to engage in the recess in the underside of the ring, to hold the wire in a circular position.

In testimony whereof I have signed my 45 name to this specification.

LEE R. TALBERT.
